UNITED STATES PATENT OFFICE.

WALTER J. ZUILL, OF SYRACUSE, NEW YORK.

WASHING-MACHINE.

1,086,635.

Specification of Letters Patent. Patented Feb. 10, 1914.

Application filed November 12, 1912. Serial No. 730,898.

To all whom it may concern:

Be it known that I, WALTER J. ZUILL, of Syracuse, in the county of Onondaga, in the State of New York, have invented new and 5 useful Improvements in Washing-Machines, of which the following, taken in connection with the accompanying drawings, is a full, clear, and exact description.

This invention relates to certain improvements in washing machines and refers more particularly to a reciprocatory dasher or dashers moving in a vat containing cleansing fluid and articles to be cleansed whereby the cleansing fluid is alternately forced and 15 drawn through such articles by pressure and suction produced by the trapping of the air in the cup shaped dashers as the latter are raised and lowered into and out of contact with the clothes and cleansing fluid.

20 The main object, therefore, of my present invention is to enable the dashers to be reciprocated and intermittently shifted rotarily by suitable mechanism extending through the cover or top of the vat without 25 shifting the axis of rotation of the dashers, except to a slight degree forwardly and rearwardly. In other words, the specific object is to increase the utility and general efficiency of this class of machines by making 30 the vat dust proof, permitting the dashers to be operated without shifting the operating lever laterally around the vat and allowing the entire cover to be removed and the dashers withdrawn from the interior of 35 the vat so as to leave the entire area of such vat open for the insertion and withdrawal of clothes or cleansing fluid.

Other objects and uses relating to specific 40 parts of the machine will be brought out in the following description.

In the drawings—Figure 1 is a transverse vertical sectional view of a hand operated washing machine embodying the various features of my invention, the supporting legs and a portion of the handle of the operating lever being broken away. Fig. 2 is a side elevation of the dasher-operating mechanism omitting the dashers and vat. Fig. 3 is a top plan of the washing machine 45 shown in Fig. 1. Fig. 4 is a horizontal sectional view of the mechanism for effecting the rotary adjustment of the dashers and adjacent portion of the dasher-reciprocating lever, a portion of the vat with the cover 50 thereon being shown in top plan.

The machine shown is technically known as

a hand washer and comprises a circular vat 1— mounted upon a suitable supporting frame 2— and provided with a cover composed of semi-circular sections 3— closely fitted upon the rim and covering the upper end or top of the vat for the purpose of excluding dust and other foreign matter and also to prevent splashing or spattering of the water over the sides and retaining the 60 heat of the cleansing fluid in the vat when heated water is used. The bottom of the vat is provided with a normally closed outlet valve 4— capable of being opened inwardly by upward pressure on the bottom thereof 65 for withdrawing the cleansing fluid from the vat when desired. Secured to and extending upwardly from the rear side of the vat is an arm or bracket 5— carrying at its upper end a removable head 6—, which 70 is normally held in operative position by a clamping screw 7—, but may be withdrawn upwardly from the end of the bracket or arm 5— when the clamping screw 7— is loosened, said clamping 75 screw also serving to hold the head against rotation on the bracket. It will be seen, on reference to Fig. 1, that this bracket 5— and head 6— are disposed wholly at the rear-side of the vat so as to permit the cover 80 85 3— to be easily and quickly placed in operative position or removed.

A hand lever 8— extends transversely of and some distance above the cover, preferably diametrically thereto, and is pivoted 90 at its rear end at 9— to the lower end of the head 6— so as to permit the free end of the lever to be rocked vertically by means of a handle 10— on its front end. In practice, the portion of the lever 8— extending rearwardly from the handle 10— is furcated or provided with opposite arms spaced a sufficient distance apart to receive between them a dasher-supporting sleeve or yoke 11— directly over the center of 100 the cover or rather substantially co-axial with the vat, said lever being pivoted at 12— to the lower end of the sleeve 11— for reciprocating the sleeve as the lever is rocked vertically in opposite directions. 105

A dasher rod or stem 13— has its upper end journaled in the sleeve or bearing 11— some distance above the top of the vat or cover 3— and its lower end is provided with opposite laterally extending arms 110 14— carrying inverted cup-shape dashers 15— as shown more clearly in Fig. 1. The

dasher rod or stem —13— is held against relative axial movement in the sleeve or bearing —11— by means of collars —16— and —17— which are secured to said rod or 5 stem and engage respectively the lower and upper ends of the sleeve or bearing, thereby imparting vertical reciprocatory movement to the dashers as the lever —8— is rocked vertically in opposite directions. The arms 10 —14— are rigidly secured to the lower end of the plunger rod or stem —13— within the vat and extend radially therefrom for receiving and supporting the dashers —15— which are also arranged within the vat 15 equal distant from the axis of the rod —13— and are rigidly secured to the outer ends of the arms —14— in substantially the same horizontal plane.

The dashers —15— are preferably circular and of slightly less diameter than the radius of the bottom of the vat so as to operate upon as large an area of the clothes as possible when reciprocated, the chambers in the bottom of the dashers serving to trap 25 the air therein when moved into contact with the water or clothes, thereby producing air cushions to aid in pressing the clothes and forcing the cleansing fluid therethrough during the downward stroke of the dashers 30 and also serving as vacuum chambers for drawing the cleansing fluid upwardly through the clothes during the upstroke of the plunger, it being understood that the upper sides of the dasher are imperforated 35 or closed to permit pneumatic pressure and suction upon the clothes as above referred to.

In order that the dashers and the operating mechanism therefor may move in vertical parallelism so as to keep both dashers in a horizontal plane, the upper end of 40 the sleeve —11— is flexibly connected by a link —18— to the upper end of the head —6—, said link being substantially parallel with the underlying portion of the 45 lever —8—.

It is now clear that the dasher —15— and its supporting plunger —13— may be reciprocated by the vertical movement of the lever —10— in opposite directions, the 50 raising of the dasher and its operating mechanism being facilitated by a retracting spring —20— having one end connected to the upper end of the head —6— and its opposite end connected to the lower end of 55 the sleeve —11—.

Suitable means is provided for limiting the upward movement of the dasher and its operating mechanism and for this purpose, I have provided the handle of the lever 60 with a rearwardly projecting loop —21— in which is mounted an adjustable limiting stop —22— positioned so as to engage the adjacent front face of the sleeve —11— when the lever —8— is raised sufficiently 65 to withdraw the dashers from contact with

the clothes, said stop also serving to prevent the arms —14— on the lower end of the plunger —13— coming in contact with the underside of the cover —3— although it is evident that by adjusting the screw —22—, 70 the dashers and operating mechanism therefor may be allowed to raise a considerable distance higher than the position shown in Fig. 1.

Rotary adjustment.—Suitable means is 75 provided for shifting the dashers —15— rotarily and intermittently about the axis of the plunger rod —13— so as to cause them to traverse the entire area of the bottom of the vat and for this purpose the rear end of 80 the lever —8— is provided with a forwardly projecting pawl —23— which is spring-pressed under its own tension into engagement with the teeth of a ratchet wheel —24— on the plunger rod —13— just beneath the collar —16— or lower end of the sleeve —11— and, therefore, below the pivotal connection —12— between the lever and sleeve so that, as the free end of the lever is rocked downwardly to force the 90 dashers into pressing engagement with the clothes, the free end of the pawl and ratchet wheel will be drawn back from the ratchet teeth the distance of one or more teeth and, when the lever is raised to its normal position, the free end of the pawl will engage 95 one of the succeeding teeth and thereby shift the plunger rod —13— and dashers rotarily a corresponding distance. In other words, by positioning the lever —8— normally in an 100 inclined plane, as shown in Figs. 1 and 2, and bringing the tooth of the pawl and ratchet wheel below the horizontal plane of the pivotal connection between the lever and sleeve —11—, it is evident that, as the lever is rocked downwardly from its normal position, the ratchet wheel will be moved forwardly or toward the handle of the lever 105 relatively to the tooth of the pawl as the lever approaches a horizontal position, this 110 forward movement being sufficient to cause the tooth of the pawl to engage the next succeeding tooth of the ratchet wheel for shifting the dashers rotarily as the lever is restored to its normal inclined position. 115

As previously intimated, the head —6— is detachably mounted upon the upper end of the bracket —5— so as to permit the dashers and operating mechanism therefor to be removed from the vat bodily when desired, the loop —21—, carrying the adjustable limiting stop —22—, being pivoted to the lever near the junction of the handle with the fork so as to permit it to be thrown back to the position shown by dotted lines, 120 thereby allowing the entire lever to be elevated to a vertical position, the rear end of the handle of said lever terminating a sufficient distance in front of the sleeve —11— to permit the lever to be rocked upwardly 125 130

over the top of the sleeve when desired to remove the dashers and operating mechanism for the vat.

Instead of removing the head —6— from the bracket —5—, the set screw —7— may be fastened and the lever rocked upwardly to nearly a vertical position or sufficient to withdraw the dashers from the top of the vat and allow the same to be rocked laterally out of alignment with said vat, thus making the entire opening available for the insertion or removal of clothes and cleansing fluid.

It has been previously stated that the dasher supporting rod —13— is held against lateral movement but it is to be understood that it is free to move backwardly and forwardly a slight distance as necessitated by the rocking of the lever to and from a horizontal position and, in order to provide for the vertical movement as well as the forward and rearward movement of the plunger, the center of the cover is provided with an opening through which the plunger rod extends.

In order that the pawl —23— may be properly adjusted relatively to the ratchet wheel —24—, its rear end is adjustably screwed to the lever by means of clamping bolts or screws —30— which are passed through elongated slots —31— in the adjacent end of the pawl as shown more clearly in Fig. 2.

What I claim is:

1. In a washing machine, a vat, a bracket secured to and rising from one side of the vat, a head on the bracket, a lever fulcrumed on the head and extending diametrically across the top of the vat, a non-rotatable sleeve pivoted to the lever some distance to the rear of the axis of the sleeve, a plunger journaled in the sleeve and extending into the vat, means for holding the sleeve and plunger against relative endwise movement, a ratchet wheel on the plunger some distance below the pivotal connection between the sleeve and lever, and a pawl on the lever engaging the teeth of the ratchet wheel at a point some distance in front of said pivotal connection.

2. In a washing machine, a vat, a cover for the vat having a central diametrically elongated slot, a lever extending over the cover lengthwise of the slot and fulcrumed at one end to swing vertically, means for holding the lever against lateral movement, a sleeve pivotally connected to the lever some distance to the rear of the axis of the sleeve, a plunger journaled in the sleeve and extending through said slot into the vat,

arms secured to and extending radially from the lower end of the plunger, dashers carried by said arms, a ratchet wheel on the plunger some distance below the sleeve and also some distance below said pivotal connection between the lever and sleeve, and a pawl on the lever and having its free end spring-pressed into engagement with the teeth of the ratchet wheel, the distance between the fulcrum of the lever and free end of the pawl being greater than the distance between said fulcrum and pivotal connection between the lever and sleeve.

3. In a washing machine, a vat, an arm secured to and rising from one side of the vat, a head mounted on the arm, means for securing the head against rotation and vertical movement, a lever pivoted to the head to swing vertically and extending diametrically across the top of the vat, a vertically disposed sleeve pivoted to the lever directly over the center of the vat, means for holding the sleeve in parallelism with the head, a spring connecting the sleeve and head and normally holding the lever above a horizontal position, a plunger rotatably mounted in the sleeve and extending into the interior of the vat, arms secured to the lower end of the plunger and extending radially therefrom, dashers mounted on said arms, means for holding the sleeve and plunger against relative endwise movement, a rocking member pivotally mounted on the lever in front of the sleeve and an adjustable limiting stop mounted on said rocking member for engagement with the sleeve to limit the upward rocking movement of the lever by the spring.

4. In a washing machine, a vat, a bracket secured to and rising from one side of the vat, a head secured to the bracket, a lever fulcrumed on the bracket and extending diametrically across the top of the vat, a sleeve pivoted to the lever directly over the center of the vat, a plunger journaled in the sleeve, means for holding the plunger and sleeve against relative endwise movement, dashers mounted on the lower end of the plunger, a spring connecting the sleeve and head for normally elevating the lever above a horizontal plane, and means mounted on the lever and coacting with said sleeve to limit the upward swinging movement of said lever.

In witness whereof I have hereunto set my hand this 6th day of November, 1912.

WALTER J. ZUILL.
